PERCUSSION FUSE FOR PROJECTILES,
BOMBS AND THE LIKE

Léon Emile Rémondy, Paris, France

Application September 27, 1934, Serial No. 745,808
In France October 9, 1933

13 Claims. (Cl. 102—39)

It is known that percussion fuses, whether intended for projectiles which are to be shot from a gun or for bombs carried by an aircraft, have to satisfy a multiplicity of conditions which it has been practically impossible to reconcile with each other heretofore. Thus, fuses intended for projectiles to be shot from a gun are required to possess extreme sensitivity, that is to say, the possibility of operation even on encountering an obstacle of very slight resistance, such as an aircraft fabric for example. At the same time, it is required that such fuses shall not allow of untimely firing in the case of an accidental fall during handling, even if the projectile falls from a relatively considerable height on to a body of considerable resistance (paved roads, rails of railway tracks and so forth). If a modern fuse, which satisfies these conditions, is to be employed for a bomb to be dropped from an aircraft, it is required that operation shall be impossible in the case of the premature fall of the bomb or of the aircraft itself from a height which may attain 40 or 50 metres, while on the other hand it is necessary that the fuse should operate on encountering even an obstacle of very slight resistance (humus, marshy ground, and so forth) when the height of fall is still of a relatively small value, as on the order of 150 to 200 metres. Finally, the fuse employed with a projectile to be fired from a gun should be so constructed that it cannot operate in any circumstances except after it has left the gun.

The present invention relates to an extremely simple and inexpensive percussion fuse which satisfies the desiderata enumerated in the foregoing.

Whereas, in the known percussion fuses, the operation of the firing mechanism is absolutely entirely the result either of the driving in of the front member of the mechanism or of the inertia of the rear member, or simultaneously of both these phenomena, the new fuse is constructed on an entirely new principle which consists in utilizing the relative inertias of the elements of the front member of the firing mechanism, which inertias come into operation after the obstacle is encountered, the said front member being constructed or designed in such a manner as to be able to dissociate under the effect of the said different inertias of its elements. The liberated rear element, the velocity of which is considerably reduced or is practically destroyed, is thus encountered by the rear member of the mechanism which continues its travel with the projectile, the shock, however, being capable of pro-

ducing ignition only if the velocity of the projectile is sufficiently high.

The dissociable front element of the firing mechanism may be given various forms of construction. 5

Different constructional embodiments of the invention to be described hereinafter are shown in the accompanying drawings wherein:

Figures 1 and 2 of the drawings show in sectional elevation the front part of a fuse body of 10 any known type provided with a mechanism according to the invention, before and after the operation of the mechanism, respectively.

Figure 3 shows in part sectional elevation the front portion of a fuse body provided with an- 15 other form of construction of the invention.

Figures 4 and 5 are sectional elevations of still another embodiment of the invention, Figure 5 showing the position which the striker may assume in case of a premature driving in thereof. 20

Figure 6 is a sectional elevation of a further modification of the invention.

Figure 7 shows a modification of the device illustrated in Figure 6.

Figure 8 is a partially sectional elevation illus- 25 trating the application of the invention to a fuse in which the intermediate firing percussion cap is omitted.

Figure 9 is a sectional elevation of another form of the invention in which the dissociable 30 member of the fuse mechanism is the percussion cap carrier.

Figure 10 is a plan view of the retaining washer of the mechanism of Figure 9.

Figure 11 is a sectional elevation of still an- 35 other form of the invention illustrating its application to a bomb.

Figure 12 is a similar view illustrating the application of a centrifugally actuated safety device 40 to one form of the present invention.

In the embodiment shown in Figures 1 and 2, *a* denotes a fuse body of known construction in which are mounted a rear firing member, preferably the percussion cap *b*, which in this particular case is fixed in its lodgment, and a front member, preferably the striker, the whole of which is denoted by *c*. In this case, the said striker is constituted in the manner known per se simply by a stem carrying the rearwardly ex- 45 tendsing percussion needle point *c*¹ and having on its forward end an enlarged head *c*² the latter being disposed and held at a suitable distance *e* from a supporting shoulder *a*¹ provided on the fuse body *a*, the retention in this position being 50 55

normally assured, likewise in known manner, for example by a frangible or shearable pin d .

According to the invention, the striker thus held at the distance e is so designed that the masses 5 forwardly, rearwardly and in the region of the retaining member d are so chosen that, under the effect of its inertia, all the part of the striker situated practically below the horizontal (as viewed in Figure 1) axial plane of the pin becomes 10 detached from the front part carrying the head c^2 after the latter, under the action of the obstacle encountered, comes to bear on the shoulder a^1 , this result being possible, however, only if the projectile possesses a suitable velocity at the 15 moment of impact and if it can retain a very considerable proportion of such velocity after encountering the obstacle.

The operation of the fuse described and shown 20 in Figures 1 and 2 may furthermore be explained as follows:

Assuming that the projectile is moving at a fairly high velocity, which it can only attain if it is shot from a gun or if it drops from an aircraft at a suitable height, of the order of about 25 100 to 150 metres, and that at this velocity the projectile encounters an obstacle of slight resistance, such as an aircraft fabric, soft ground and so forth, the whole of the extremely light striker will be driven back by its head c^2 , which will 30 effect the shearing of the pin d , the resistance of which should be in proportion to the mass of the striker and may consequently be selected sufficiently weak. When the striker in its relative 35 inward movement is arrested on the shoulder a^1 , it will be immediately driven forward by the projectile which, due to the low resistance of the obstacle, is capable of advancing at a still considerable velocity. This ability of the projectile to advance may be assisted moreover by a relatively 40 tapered form of the front part of the ogive of the projectile and of the fuse body. To this extremely sudden driving by the projectile, which takes place at the very instant the head c^2 strikes the shoulder a^1 , the rear and front elements of 45 the striker offer different resistances, by reason of their suitably chosen different masses, which tends to cause a dissociation, this being furthermore ensured by weakening sufficiently the zone of separation between the rear element carrying 50 the needle point c^1 and the front element carrying the head c^2 . This weakening may be merely due to the hole provided for the passage of the pin d ; on the other hand, the dissociation may be assisted still further by weakening the cross-section 55 in the zone of the pin, for example by turning, milling and so forth.

As above pointed out, the shock of the shoulder a^1 against the indeformable head c^2 , followed instantaneously by the driving of the striker by the 60 projectile, brings the inertia of the needle point carrying rear element c^1 of the striker violently into play and causes the dissociation between the rear element carrying the needle point c^1 and the front element carrying the head c^2 . Of course, 65 the distance e between the head c^2 and the shoulder a^1 is less than the distance f separating the extremity of the needle point c^1 from the percussion cap b , so that even in the case of untimely rupture of the pin d , the needle point of 70 the striker cannot meet the percussion cap, it being impossible for such meeting to take place unless the elements of the striker are dissociated.

Figure 2 shows the percussion cap impaled on the striker after the separation or dissociation 75 between the two elements of the latter.

Of course, the suitable distribution of the masses in the striker as a whole may be obtained in various ways. Thus, it is possible to provide a recess in the portion carrying the head.

In the construction illustrated in Figure 3, instead of the striker being constituted by a single body, the masses of which are suitably distributed with a view to dissociation into two elements situated respectively above and below the region of the retaining member, the said striker is constituted by two distinct elements normally secured together but separable upon impact. The front element carrying the head c^2 is in this case fixed to the fuse body a by the pin d which also serves to retain the whole of the striker in inoperative 10 position, while the rear element c^1 which carries the needle point is fitted in a cavity of the stem c and is normally secured to the said stem by a frangible or shearable member such as the pin g , any forward displacement of c^1 relatively to c^2 15 being prevented for example by a supporting collar c^3 formed on the element c^1 . As in the preceding example, a distance e , less than the distance f separating the percussion cap b from the point of the striker, is left between the head c^2 20 and a shoulder a^1 of the fuse body.

The operation of the fuse according to Figure 3 is quite similar to that of the fuse shown in Figures 1 and 2. On encountering an obstacle of slight resistance, such as an aircraft fabric or 30 soft ground for example, the pin d is sheared by the driving in of the indeformable head c^2 and the latter moved rearwardly until it strikes the shoulder a^1 of the fuse body with a sudden shock, resulting in the shearing of the pin g . Immediately 35 after this shock, the whole of the striker thus liberated from the fuse body is driven by the projectile which, due to the relatively slight resistance of the obstacle, may continue its travel. The inertia of the needle-point-carrying rear element 40 c^1 of the striker then comes into play, the said element tending to lag behind and thereby causing the dissociation between the rear element and the front element and the operation of the fuse due to the meeting of the percussion cap b and 45 the needle-point-carrying element c^1 separated from the head-carrying element c^2 .

In the embodiment which has just been described, it is possible, in order to increase the mass of the needle-point-carrying rear element 50 of the striker without increasing its bulk, to extend the said element forwardly until it contacts the head c^2 , a slit being left for the passage of the pin d , as shown in dot-and-dash lines in Figure 3.

Figure 4 shows a variation of the constructional form of Figure 3, in which the two distinct elements, needle point carrier c^1 and head carrier c^2 are assembled together by the same frangible or shearable member d which normally retains the 60 whole of the striker fixed with respect to the fuse body a .

Figure 4 also shows a particular arrangement of the rear member of the firing mechanism, the said arrangement being equally applicable to all the forms of construction of the invention. In order to prevent any meeting between the needle point of the striker and the percussion cap in the case of the premature rupture of the retaining member of the striker or of the member assembling together the elements of the said striker, while the projectile is travelling through the gun barrel, the percussion cap carrier, as shown in Figure 4, is disposed in a recess a^2 of the fuse body where, instead of being fixed, the said percussion 75

cap carrier is yieldingly urged against the front part of the said recess by means of a resilient member h , such as a spring, a cylinder of felt or cork, and so forth. It will be appreciated that, on the initial movement of the projectile at the moment of firing and during its acceleration, the percussion cap carrier is held back by its inertia which is sufficient to compress the resilient support h . Once the acceleration has ceased, the said support resumes its preponderance and fixes the percussion cap carrier in the position indicated in Fig. 4.

Figure 5 shows the percussion cap carrier of Figure 4 driven towards the bottom of its recess and the support h compressed. The figure shows the position which the striker may assume in the case of premature rupture of the pin d .

In the construction shown in Figure 6, which may be considered as a modification of the device shown in Figure 3, the striker is constituted by two elements: a head-carrying front element c^2 and a needle-point-carrying rear element c^1 , connected together by means of a shearable assembling pin g , the whole of the two elements being normally secured to the fuse body a by the usual pin d . In this construction, however, the rear element c^1 is not prevented from moving forward. On the contrary, the dissociation between the said elements c^1 and c^2 is brought about upon impact, under the effect of the inertia of the element c^1 which moves forward, shearing the pin g . Once the elements c^1 and c^2 are dissociated, operation take place as in the preceding examples.

In the modification illustrated in Figure 7, the dissociable striker comprises a head-carrying element c^2 and a needle point-carrying element c^1 connected together by means of the shearable retaining pin d , which passes through the element c^1 and at the same time through the tail-piece i^1 of a plunger i , the head of which bears by means of a shoulder against the base of the head-carrying element c^2 . A clearance j is left between the said head i and the front end of the hollow stem of the element c^2 .

Upon impact, the plunger i moves forward relatively to the striker assembly, shearing the pin d and thereby effecting the dissociation of the elements c^1 and c^2 .

In all the forms of construction which have just been described, it has been specified that the distance e between the head c^2 of the dissociable striker and the shoulder a^1 of the fuse body was necessarily less than the distance f separating the needle point c^1 from the percussion cap b . It should be noted that the said distance f may be made large enough to delay in a suitable manner the meeting of the striker and the percussion cap. It is thus possible to delay the operation without employing a delay-action composition, solely on account of the interval left between the two elements of the mechanism.

As shown in part sectional elevation in Figure 8, it is also possible to employ the dissociable striker according to the invention by simply combining it with the detonating percussion cap k , the usual intermediate firing percussion cap b being in this case omitted.

As stated in the foregoing, the front dissociable member of the mechanism, instead of being constituted by the striker, may be constituted by a percussion cap carrier, the rear fixed member of the mechanism being in this case a percussion needle point or any other suitable shock member.

Figure 9 shows in sectional elevation such a

constructional example. In this construction the front head carrier c^2 is made in the form of a socket in the interior of which is disposed a percussion cap c^1 constituting the rear element of the dissociable unit member c^2-c^1 . The unit c^2-c^1 may be normally retained in a fixed position with respect to the fuse body a , for example, by means of a washer d having projecting pieces, such as that shown in Figure 10, which is pierced by a central hole d^1 and is fixed securely in the fuse body by the projecting pieces d^2 . Of course, the masses c^1 and c^2 will be suitably chosen to ensure operation in the same manner as in the constructional examples described hereinbefore. On impact, the washer is sheared from its projecting pieces d^2 and the two elements c^1 and c^2 are forced rearwardly together until the head c^2 strikes shoulder a^1 and is suddenly arrested in its rearward movement. The inertia of c^1 during the continuation of the movement of the projectile will delay the forward movement of the percussion cap which will thereupon be struck by the fixed striker b which continues its movement with the projectile.

Figure 11 shows in sectional elevation an example of the application of the invention to a bomb, in which the dissociable front member c^2-c^1 , constituted by the striker, is carried by a cap m or any other equivalent protection device, retained on the fuse body, for example, by means of a stud m^1 engaged in a slot a^3 . The cap, likewise in known manner and as shown in Figure 11, may be retained in the position of this figure by a collar n adapted to be withdrawn upon the bomb being dropped, and which if desired may constitute one of the suspension members of the bomb.

Figure 12 shows in sectional elevation the use of the device of a dissociable front member similar to that shown in Figure 4 in combination with a safety device o , adapted to be withdrawn under the effect of the centrifugal force, of any known type and disposed at a suitable point, for example at the rear of the dissociable member c^2-c^1 of the mechanism. In this example, the safety device is constituted by a spring bolt, the nose of which remains in the path of the member c^2-c^1 as long as the effects of the centrifugal force have not made themselves felt sufficiently to ensure the complete withdrawal of the said nose.

A projectile provided with any one of the forms of construction which have just been described is, as indicated in the foregoing, ensured against any premature operation during its travel in the interior of the gun barrel. It has been shown in the foregoing that the mechanism of the fuse operates, upon encountering an obstacle, so long as the nature of the obstacle is such that the projectile may continue its movement with a sufficient velocity during a suitable time for effecting the dissociation between the elements of the dissociable front member.

It obviously results from this fact that, if the velocity of the projectile is insufficient, the dissociation between the elements c^1 and c^2 is impossible; and it follows that a projectile, even if it strikes a very resistant obstacle, cannot burst on account of the operation of the firing mechanism, the dissociation of the elements of the dissociable front member not being effected and the rupture of the pin or other retaining member of the dissociable member of the mechanism being incapable alone of bringing about the operation of the fuse. This quality enables the invention to be utilized for projectiles intended for firing against aerial objectives. In the case in which

the projectile does not hit the objective, it may fall without the mechanism of the fuse operating, whenever such fall takes place on hard ground or any other resistant obstacle (such as pavings, roads, buildings, and so forth).

If it is desired to ensure the operation of the fuse on encountering a resistant obstacle, it is possible, as shown in Figure 12, to provide the front element c^2 of the dissociable member c^2-c^1 10 with a projection p which extends forwardly beyond element c^2 a distance greater than the distance e between the rear surface of said element and the shoulder a^1 of the fuse body. Upon initial encounter of the end of projection p with a 15 resistant obstacle, the dissociable member c^2-c^1 is driven rearwardly as a unit so as to rupture the retaining member d and until engagement between head c^2 and shoulder a^1 , at which time a portion of projection p will still extend beyond 20 the end of fuse body a . This remaining portion will then be crushed as the projectile continues to move until the end of the fuse body also comes into contact with the obstacle. During the 25 crushing of the projection p , the projectile will travel through a suitable distance with an appreciable residual velocity, which is sufficient to ensure the operation of the mechanism by the dissociation of the two element c^2 and c^1 .

Although a number of different forms of the 30 invention have been described and illustrated in the accompanying drawings, it will be obvious that the invention is not limited to the specific structures disclosed but is capable of a variety of mechanical embodiments. Various changes, 35 which will now suggest themselves to those skilled in the art, may be made in the form, details of construction and arrangement of the parts without departing from the spirit of the present invention. Reference is therefore to be had to 40 the appended claims for a definition of the limits of the invention.

What is claimed is:—

1. In a percussion fuse mechanism, the combination with a fuse body of a rear fuse member 45 fixed with respect to said body, a front fuse member comprising at least two separable elements normally united together, means normally securing all of the elements of said front member in fixed positions relative to the fuse body but rupturable upon impact so as to permit said elements to move rearwardly with respect to said body, means for limiting the extent of rearward movement of the frontmost element of said front member, and means normally uniting said elements but rupturable after impact so as to separate the rearmost element from the frontmost element, the mass of said rearmost element being such that after separation from the frontmost element and engagement of the latter with said 55 limiting means, and during continued forward movement of the fuse body, the inertia of said rearmost element is sufficient to bring it into percussion contact with the rear member of the fuse mechanism.

65 2. A fuse mechanism according to claim 1 wherein the rear fuse member is disposed at such a distance from the front member that percussion contact between the rearmost element of the front member and the rear member is delayed 70 for a suitable length of time after dissociation of the front member into its separate elements, whereby the use of a delay-action composition may be eliminated.

75 3. A fuse mechanism according to claim 1 wherein the rear fuse member is normally fixed

only as to forward movement relative to the fuse body, said mechanism including a resilient support interposed between said rear fuse member and a fixed portion of the fuse body to the rear thereof whereby, when said fuse mechanism is used with a projectile, the rear fuse member is set back into an inoperative position when the projectile is fired from the gun. 5

4. A fuse mechanism according to claim 1 including means for positively preventing rearward movement of the front fuse member, when the fuse mechanism is used with a projectile, until after the projectile is in flight, said means being then withdrawn into inoperative position under the influence of centrifugal force. 10 15

5. In a percussion fuse mechanism, the combination with a fuse body of a rear fuse member comprising a percussion cap fixed with respect to said body, a front fuse member having a body portion slidably mounted in the fuse body and 20 a percussion cap striker on the rear end thereof, means normally securing said front member to said fuse body but rupturable upon impact so as to permit said member to move rearwardly with respect to said body, and means for limiting the 25 extent of said rearward movement of said front member, the body portion of said front member being weakened at one point in its length and the masses of said member forward and rearward of said weakened point being such that, 30 upon engagement of said member with said limiting means, the rear striker-carrying portion thereof is detached from the front portion under the effect of its inertia and, during continued forward travel of the fuse body, is brought into 35 firing contact with the percussion cap.

6. In a percussion fuse mechanism, the combination with a fuse body of a rear fuse member comprising a percussion cap fixed with respect to said body, a front fuse member having a body 40 portion slidably mounted in the fuse body, an enlarged head on the forward end thereof and a percussion cap striker on the rear end thereof, a frangible pin passing through said body portion and anchored at its ends in said fuse body, said 45 pin normally securing said front member to said fuse body but rupturable upon impact so as to permit said member to move rearwardly with respect to said fuse body, and a shoulder fixed with respect to said fuse body for limiting the extent 50 of rearward movement of said head-carrying portion of said front member by engagement therewith, the body portion of said front member being weakened in the region of said pin and the masses of said member forward and rearward of 55 said weakened point being such that, upon engagement of said head with said shoulder, the rear striker-carrying portion of said member is detached from the head-carrying portion under the effect of its inertia and, during continued forward travel of the fuse body, is brought into 60 firing contact with the percussion cap.

7. In a percussion fuse mechanism, the combination with a fuse body of a percussion cap fixedly mounted in said body, a striker member slidably mounted in said fuse body forward of said 65 percussion cap, said striker member including a front element adapted to receive the impact and a rear element carrying a striker point, means normally securing said striker member to said 70 fuse body but rupturable upon impact so as to permit said member to move rearwardly with respect to said fuse body, means normally securing said front and rear elements of said member together but rupturable upon rearward move- 75

ment of said front element, and means for limiting the extent of rearward movement of said front element, the mass of said rear element being such that after rupture of said last mentioned securing means and engagement of said front element with said limiting means, and during continued forward travel of the fuse body, the inertia of said rear element is sufficient to bring its striker point into firing contact with 10 said percussion cap.

8. In a percussion fuse mechanism, the combination with a fuse body of a rear fuse member fixed with respect to said body, a front fuse member comprising a front element and a rear element, said front element carrying an enlarged head extending beyond the fuse body and adapted to receive the impact, a shearable member normally securing said front element to said fuse body but rupturable upon impact so as to permit rearward movement of said element relative to said fuse body, a second shearable member normally securing said rear element to said front element, and a shoulder formed on said fuse body for limiting the extent of rearward movement of 15 said front element by engagement with said head, the mass of said rear element being such that after impact and upon engagement of said shoulder with said head said second shearable member is ruptured so as to separate the rear element from said front element, continued forward travel of the fuse body then bringing the rear element into percussion contact with the rear member of the fuse mechanism.

9. In a percussion fuse mechanism, the combination with a fuse body of a percussion cap fixedly mounted in said body, a striker member slidably mounted in said fuse body forward of said percussion cap, said striker member including a front element carrying an enlarged head extending beyond the fuse body and adapted to receive the impact and a rear element carrying a striker point, a shearable member normally securing said front element to said fuse body but rupturable upon impact so as to permit said element to move 20 rearwardly with respect to said fuse body, a second shearable member normally securing said rear element to said front element, means for preventing forward movement of said rear element relatively to said front element, and a shoulder carried by said fuse body for limiting the extent of rearward movement of said front element by engagement with said head, the mass of said rear element being such that upon engagement of said head with said shoulder the inertia 25 of said element ruptures said second shearable means so as to disconnect said elements from one another and, during continued forward travel of the fuse body, brings its striker point into firing contact with said percussion cap.

10. In a percussion fuse mechanism, the combination with a fuse body of a percussion cap fixed with respect to said body, a striker member comprising a front element and a rear element slidably mounted in said fuse body forward of said percussion cap, said front element carrying an enlarged head extending beyond the fuse body and adapted to receive the impact, said rear element being mounted within said front element for movement rearwardly but not forwardly relative thereto and carrying a striker point, a shearable pin normally securing said front element to said fuse body but rupturable upon impact so as to permit rearward movement of said element relative to said fuse body, a second shearable pin 30 normally securing said rear element to said front

element, and a shoulder formed on said fuse body for limiting the extent of rearward movement of said front element by engagement with said head, the mass of said rear element being such that after impact and upon engagement of said shoulder with said head said second shearable pin is ruptured so as to separate the rear element from said front element, continued forward travel of the fuse body then bringing the striker point of said rear element into firing contact with the 10 percussion cap.

11. In a percussion fuse mechanism, the combination with a fuse body of a percussion cap fixedly mounted in said body, a striker member slidably mounted in said fuse body forward of 15 said percussion cap, said striker member including a front element carrying an enlarged head extending beyond the fuse body and adapted to receive the impact and a rear element carrying a striker point, a shearable pin passing through both said front and rear elements and anchored at its ends in said fuse body, said pin normally securing said elements together and to said fuse body, the connection between said elements and the fuse body being rupturable upon impact so as 20 to permit said elements to move rearwardly with respect to said fuse body, means for preventing forward movement of said rear element relatively to said front element, and a shoulder carried by said fuse body for limiting the extent of rearward 25 movement of said front element by engagement with said head, the mass of said rear element being such that upon engagement of said head with said shoulder the inertia of said element ruptures the connection between said elements so as 30 to disconnect them one from the other and, during continued forward travel of the fuse body, brings its striker point into firing contact with said percussion cap.

12. In a percussion fuse mechanism, the combination with a fuse body of a rear fuse member fixed with respect to said body, a front fuse member comprising a front and a rear element normally united together, said front element having an enlarged head thereon, means normally securing said front member to the fuse body but rupturable upon impact so as to permit said member to move rearwardly with respect to said fuse body, a shoulder carried by said fuse body for limiting the extent of rearward movement of the front element of said front member by engagement with said head, a crushable impact receiving member projecting forwardly from said enlarged head and extending beyond the end of said fuse body a distance greater than the normal distance between said head and said shoulder, and means normally securing said front and rear elements together but rupturable after impact so as to separate the same, the mass of said rear element being such that after separation 40 from said front element and engagement of said head with said shoulder, and during continued forward travel of the fuse body until said impact receiving member is crushed to the level of the front end of the fuse body, the inertia of said 45 rear element is sufficient to bring it into percussion contact with the rear member of the fuse mechanism.

13. In a percussion fuse mechanism for a projectile or the like, the combination with a fuse 50 body of a fixed rear fuse member, a front fuse member comprising a plurality of separable elements normally securely connected to one another, a retaining member normally rendering said front fuse member immovable relatively to 55

the fuse body, said retaining member being so constructed and arranged that upon impact against an obstacle of insufficient resistance to arrest the flight of the projectile the connection between said front fuse member and the fuse body is broken and said fuse member moves rearwardly relatively to the fuse body under the force of impact, and means for limiting the rearward movement of one of the elements of said front fuse member, at least one other of said elements being unlimited in its movement by said last

named means, the normal connection between said elements of the front fuse member being such that after impact and upon engagement of one of said elements with the limiting means said connection is ruptured due to the inertia of the unlimited element and the latter is free to move rearwardly into percussion contact with the rear fuse member during continued forward travel of the projectile.
